RECLINING CHAIR

Joseph R. Thomas, Chicago, Ill.

Application December 3, 1947, Serial No. 789,537

12 Claims. (Cl. 155—116)

1

This invention relates in general to a reclining chair in which a plurality of connected sections are movable at different angles to swing the back and an intermediate section relative to the seat to form different upright and inclined variations of the sections.

An important object of the invention is to provide an inclinable chair with connected seat, back, and intermediate sections which will assume any relative inclined position with respect to each other in which they are placed, and will retain this position until they are changed either by an occupant of the chair or by manually changing the inclination of the sections when not occupying the chair.

A further object of the invention is to mount the connected sections in a chair frame so that the inclination of the back relatively alters the positions of the sections with respect to each other, advancing the seat section forwardly as the back section is inclined downwardly and simultaneously inclining the intermediate section.

A further object of the invention is to provide a plurality of connected seat, back, and intermediate sections for a folding chair which are adapted to be assembled independently and mounted in chair ends of various designs.

Other objects of the invention will appear in the specification and will be apparent from the accompanying drawings, in which,

Fig. 1 is a perspective of a reclining chair in accordance with this invention showing part of the chair cover and part of the covering broken away to illustrate the connection of the connected sections in a frame;

Fig. 2 is a detail sectional view showing the connections of one of the cushions by means of a cover to one of the section frames;

Fig. 3 is a sectional side elevation showing the connected sections of Fig. 1 in a partially inclined and reclining position;

Fig. 4 is a view similar to Fig. 3 showing the connected sections with the back in a substantially upright position;

Fig. 5 is a detail edge view of the mounting block and plate shown in Fig. 4;

Fig. 6 illustrates a modification of the connection and mounting of the seat, back, and intermediate sections;

Fig. 7 illustrates another variation of the mounting and connection of the seat, back, and intermediate sections;

Fig. 8 illustrates another method of mounting the forward end of the seat section with stops to

2

limit its movement in both forward and rearward directions; and

Fig. 9 illustrates a mounting of the front of the seat section upon a roller which allows it to move freely within limits in both directions.

Many reclining chairs are of the type in which it is necessary to adjust the relative inclination of the back and seat, and require a complicated or cumbersome fastening or holding means to secure the sections in their relative adjusted positions. The present invention not only provides a chair with relatively inclinable sections, but also the connected sections are so mounted and supported in the chair frame that they tend to retain any position in which they are set, making it unnecessary to frequently mechanically adjust, lock or fasten any one of the sections in any adjusted position. The change in position may usually be accompanied by pressure of the body of a person within the chair, and since the chair sections are all connected, a continuous supporting surface is provided from the front of the seat to the top of the back. For securing the sections temporarily in any adjusted position, a simple fastening bolt may be used.

Referring now more particularly to the drawings, the relatively inclinable seat sections are mounted in a chair frame comprising side arm frames 18, a front board 12, a front metal angle cross brace 14, and a rear metal angle cross brace 15. Sometimes the front board is connected to the front of the seat section, but usually it is connected between the front posts of the chair frame or to the front cross brace 14 if one is attached.

Connected back, seat, and intermediate sections, 16, 17 and 18, respectively, are each preferably formed of metal angle bars forming the marginal frame of each section with a mattress 40 supporting resilient fabric 20 composed of wire and springs extending across the sections between the marginal frames and extending continuously lengthwise from the top of the back section to the front of the seat section.

The seat section preferably comprises a rear downwardly bent portion or attached side arms 21 connected by a crosspiece 22 and having a strengthening link 23 in the angle between each of the downward extending arms and the crosspiece and another strengthening link 24 between each downward extending arm and the side of the seat section.

The back section may consist of a single bar, bent to form sides 25, the lower ends of which have a cut-out 26 to receive ends of side bars

27 of the intermediate section, each connected thereto by a pivot 28. The other end of each side bar 27 is connected by a pivot 29 with the projecting end of a strap 30 secured to the rear extremity of the seat section 17 by fastening rivets 31. Thus the seat, back, and intermediate sections form a continuous connected support with pivots at both ends of the intermediate section joining it to the back and seat respectively. The downward cross brace at the rear end of the seat section is of sufficient strength to support the spring fabric 20 intermediate the ends of the connected frames so that any suitable cushions or upholstery may be applied thereto. The preferred covering comprises a seat cushion 32 and a combined back and intermediate section cushion 34 of a flexible and resilient material such as sponge rubber, held in place by a cover 36 of fabric or any other suitable material, the fabric extending over the edge of a metal frame as shown in Fig. 2 and suitably connected by upholstery tacks 37 to a fastening strip 38 secured to the inside of the angle bar by fastening bolt 39. Other means of fastening the upholstery or cushions in place may be employed as this construction is not a part of the present invention.

To mount the connected frame sections for movement in a chair frame, one end of a link 40 is connected by a pivot 41 with the under side of the seat section and the other end of the link is connected by a pivot 42 with a mounting bar 44 adapted to be secured to the inside of the chair arm frame 10 by fastening screws 45 or any other suitable means.

The rear end of the seat section is supported by a lever 46 having a pivot 47 at the lower end of the downwardly extending arm 21 and at the lower end of the lever. Near the upper end of the lever, it is connected by a pivot 48 with the upper end of the supporting bar 44 and with the upper arm of the lever projecting above the pivot.

At each rear lower side of the back section 16 is a projecting rib 50 extending from the lower end of the side rail 25 and preferably projecting angularly below it where the extremity is connected by a pivot 51 with one end of a link 52, the other end of which is connected by a pivot 53 with the upper end of the lever 46. With this coordinating connection, any change in the angular movement of the back section will cause a change in the forward or rearward displacement of the seat section 17, limited by the connection of the side bars 27 of the intermediate section 18.

In order to properly guide and retain the sections in reclining positions, each side bar 27 of the intermediate section is connected by a pivot 54 about centrally of its ends, with one end of a link 55, the other end of which is connected by a pivot 56 with the outer side of a supporting plate 58, the upper end of which is offset (see Fig. 5) to allow the link 52 to move downwardly at the inside of the plate. The plate 58 may be secured to a spacing block 59 which in turn is secured to the adjacent inside rear edge of the side arm frame 10 as shown.

With this construction, the intermediate section may rock freely upwardly and downwardly upon the links 55 at each side thereof for positioning the intermediate section in alignment with the back section as shown in Figs. 1 and 4, or in a more or less inclined position as shown in Fig. 3.

To additionally strengthen and space the side

bars 27 of the intermediate section apart, a U-shaped cross frame 60 may be secured at its extremities to the side bars 27 by rivets 61 and held in distended position by an angle brace 62 at each end.

Instead of connecting the link 52 to the upper end of the lever 46, a construction as shown by Fig. 6 may be substituted in which a link 66 may be connected at its lower end by a pivot 67 with the lower side arm 21 of the cross brace of the seat section, and the upper end of the link is connected by a pivot 68 with the upper end of the supporting bar 44 at approximately the location of the pivot 48 as shown in Figs. 3 and 4. Instead of connecting the link 52 from the back section to the upper end of the lever 46, a link 70 as shown in Fig. 6 is connected by a pivot 71 with a strap 72 attached at the rear end of the side bar of the seat section 17 and connected thereto by fastening rivets 73. The side bars 27 of the intermediate section 18 are connected as previously described to the offset plates 58 by links 55.

In the modification shown in Fig. 7, a supporting link 74 is connected by a pivot 75 to the side arm frame 10 at the rear of the seat section, and the upper end of the link is connected by a pivot 76 which extends through the end of strap 39 attached at the rear of the seat section and also through the adjacent end of the side bar 27 of the intermediate section 18. Thus the rear of the seat section and the lower end of the intermediate section are connected and rocked together. The lower end of each rib 50, projecting from the back section, is connected by means of a link 78 having a pivot 79 at one end connecting it to the end of the rib 50 and by a pivot 80 at the other end connecting it to the link 74 intermediate the ends thereof. The intermediate section 18 is connected at each side by means of a link 55 extending to a plate 58.

In each of the forms, a balancing or counterbalance spring or springs 82 are connected between the lower end of the seat section brace and the cross brace 15 at the rear of the connected frames 10.

At the front of the seat section, its movement may be limited by angularly disposed stops 84 and 86 carried by the mounting bar 44 and engaging opposite edges of the supporting link 46 in its rearward and forward movements respectively.

Instead of mounting the front end of the seat section upon links to swing forwardly and rearwardly, each side bar of the seat section may be supported by a roller 87 mounted upon a pivot 88, secured to the adjacent inside surface of the frame end 10. Limit stops 89 may be secured to each side bar of the seat section relatively in front of and behind the roller 87, thereby limiting the movement of the seat section in that direction.

The front end of the seat frame may be supported by a downwardly extending braced leg 90 (Fig. 8) to the lower end of which a link 91 is pivoted having its upper end connected to a fixed pivot 92 supported by the frame 10, the opposite swinging movements of the link being limited by the angularly disposed stops 94 and 96 also secured to the chair frame end 10.

In this construction, the pivotal connections between the sections and the mounting parts are frictionally resistant so that the parts do not move freely and easily, but must have some pressure applied thereto for relative movement. This

is effected in part by the rivet connections and the pivotal mounting between the sections, the mounting of the sections in the frame, the relative spacing of the links and levers, and the balancing and counter-balancing of the chair sections in the supporting frame by means of counter-balancing springs. The resistance is such that when the chair sections are moved, for example, to upright position, they tend to remain in that position, and unless the back is pressed rearwardly by a person in the chair pushing rearwardly upon the back, or the seat is pushed forwardly or backwardly, the chair sections will tend to remain in that position, and they will also tend to remain in any relative inclined position in which they are pushed or moved by a person within the chair or occupying the sections from without the chair. Thus it is usually unnecessary to have any operating or inclining mechanism or locking parts, and the chair sections readily assume a balanced and stationary position at any angle in which they are placed.

If desired, a simple positive locking means may be provided comprising a pin 97 slideable in a bracket 98 secured to the outer side of the frame of the seat section 17 and having a pointed extremity adapted to engage in any one of a number of perforations 99 in one web of an angle bar 100 attached through the other web to a suitable fixed support such as the mounting bar 44. The pin has a head 101 by which it may be raised and lowered in the bracket and engaged in and disengaged from the perforations 99.

These constructions are prefabricated and assembled upon the mounting bars 44 and the supporting plates 58 so they may be applied and connected to chair side arm frames 10 by simply attaching the bars and plates in the proper relative positions. This makes it easier to connect the sections and apply the cushions and upholstery, to finish the side arm frames, and to mount the sections in different frames, if desired. It is also easier and less expensive to pack and ship the sections and frames from a manufacturer to a dealer, and the parts occupy less storage space in a knock-down condition.

While the preferred constructions have been described in some detail, they should be regarded by way of illustration and example rather than as a restriction and limitation of the invention, as various changes in the construction, combination, and arrangement of the parts may be made without departing from the spirit and scope of the invention.

I claim:

1. A reclining chair, comprising a chair frame, pivotally interconnected seat, back, and intermediate sections movable relatively with respect to each other in a predetermined manner, means for connecting the seat and intermediate sections for swinging movement in the chair frame, and means connected to the back section and to one other section for moving it in a predetermined manner relatively to the other sections as the other two sections swing in the frame and for changing the angular positions of all the sections with respect to each other.

2. A reclining chair, comprising a chair frame, seat, back, and intermediate sections pivotally interconnected together for relative movement with respect to each other in a predetermined manner, means to mount the seat section on the inside of the chair frame to swing forwardly and rearwardly in the frame, means to mount the intermediate section on the chair frame for swing-

ing movement about the inner end of the seat section, and means connected to the back section and to one other section for moving it in a predetermined manner relatively to the other sections as the seat section swings forwardly or rearwardly and causing the intermediate section to swing relatively to both of the other sections.

3. In a reclining chair, a chair frame, a seat section and means to mount it for forward and rearwardly swinging movement in the frame, an intermediate section pivotally connected at the rear of the seat section, means connecting the intermediate section to the chair frame whereby the intermediate section may pivot and move upwardly and downwardly when the seat section is moved forwardly and rearwardly, a back section pivotally connected to the free end of the intermediate section, and means including at least one link connecting the back section to the inner end of the seat section so that the angular positions of all of the sections are changed with respect to each other when either the seat section or the back section is moved relatively in the frame.

4. In a reclining chair, a chair frame, a seat section and means for mounting the seat section to swing forwardly and rearwardly in the chair frame, an intermediate section pivotally connected at the rear end of the seat section and extending relatively upward therefrom, link means for mounting the intermediate section on the chair frame to swing to more or less inclined positions depending upon the forward swinging movement of the seat section, a back section pivoted to the upper end of the intermediate section, and a support for the back section comprising a rib extending downwardly from each side thereof, a link pivoted at one end to the rib and pivoted at the other end to mounting means at the rear of the seat section.

5. In a reclining chair, a chair frame, a seat section and means including levers at the rear end of the section pivoted intermediate their ends to the adjacent chair frame for supporting the rear end of the seat section for forward and rearward swinging movement, an intermediate section pivotally connected at one end to the rear of the seat section, a back section pivotally connected to the other end of the intermediate section, means mounting the intermediate section in the frame for swinging movement forwardly and rearwardly with the seat section, and means including a link pivotally connected to the lower end of the back section at each side thereof, and the other end of the link pivotally connected to

the upper end of the adjacent lever supporting the rear end of the seat section so that the forward movement of the seat section swings the back section rearwardly upwardly and inclines the intermediate section accordingly.

6. In a reclining chair, a chair frame, a seat section mounted in the chair frame to swing forwardly and rearwardly and including a mounting lever connected at its lower end to the seat section, pivoted intermediate its ends to the adjacent side of the chair frame and having a portion extending above the pivot, an intermediate section pivotally connected at one end to the rear end of the seat section, a back section pivotally connected to the other end of the intermediate section, means mounting the intermediate section on the chair frame to swing forwardly and rearwardly with the seat section, a supporting rib extending downwardly at each side of the back section, and a link pivotally connected at one end

to the rib and at the other end to the upper portion of the mounting lever for the seat section.

7. In a reclining chair, a chair frame, a seat section having a rear downwardly extending cross brace, means mounting the seat section for swinging movement in the chair frame including a lever pivoted at its lower end to one side of the cross brace and a fixed pivot near its upper end connected to the chair side frame, a portion of the lever extending above the fixed pivot, an upwardly inclined intermediate section pivotally connected to the rear of the seat section, links pivotally mounting the intermediate section to swing forwardly and rearwardly with the seat section, a back section pivotally connected to the upper end of the intermediate section, a supporting rib extending downwardly at each side of the back section and a link pivotally connected at one end to the supporting rib and at the other end to the upper extremity of the upwardly projecting lever portion, the movement of one section effecting a corresponding movement of the other sections.

8. In a reclining chair, a chair frame, a seat section and means mounting it for swinging movement forwardly and rearwardly in the chair frame, the rear mounting means comprising a brace extending downwardly at the rear of the seat section, a lever connected at its lower end to the lower end of the brace and connected intermediate its ends to a fixed point of the chair frame, an intermediate section pivotally connected at one end to the rear of the seat section, a back section pivotally connected to the other end of the intermediate section, means mounting the intermediate section for upward inclined movement with respect to the seat section, said means comprising a link connected at one end between the front and rear of the side of the intermediate section, an offset plate secured to the inside of the chair frame, the other end of the link pivoted to the inner side of the offset plate, a downwardly extending rib at each side of the back section, another link connected at one end to the rib and connected at the other end to the upper end of the lever which supports the rear of the seat section and this link being movable at the outside of the adjacent link for mounting the intermediate section and movable between the said offset plate and the inside of the seat frame from which it is offset.

9. In a reclining chair, a chair frame, a seat section and a back section pivotally interconnected by an intermediate section, swinging means pivoted to the inside of the chair frame for mounting the seat section to swing forwardly and backwardly in the chair frame, links connecting the intermediate section in an upwardly inclined position and movable forwardly and rearwardly with the seat section, a supporting rib extending downwardly at each side of the back section, link means connected at one end to the lower end of the supporting rib and at the other end to one of the swinging means pivoted to the inside of the adjacent chair frame, and spring means connecting the rear of the seat section to the chair frame and tending to move the seat section rearwardly and to align the intermediate section and the back section in an inclined position at the rear of the seat section.

10. A reclining chair, comprising a chair frame, pivotally interconnected seat, back, and intermediate sections movable relatively with respect to each other in a predetermined manner, means for connecting the seat and intermediate sections

to the inside of the chair frame for swinging movement in the chair frame, means connected to the back section and to one other section for moving it in a predetermined manner relative to the other sections and for moving the other two sections for swinging movement in the frame, and spring means connecting the rear of the seat section and the rear of the chair frame tending to move the seat section rearwardly in the chair frame and to align the intermediate section and the back section in an inclined position at the rear of the seat section.

11. In a reclining chair, a chair frame, pivotally interconnected seat, intermediate and back sections, means mounting the seat section for forward and rearward swinging movement in the chair frame, and comprising an upwardly extending lever pivotally secured to the chair frame and pivotally connected at its lower end to the rear end of the seat section, means mounting the intermediate section on the chair frame in an inclined position extending upwardly from the rear of the seat section, the intermediate section being adapted to be inclined to a lesser degree by the forward movement of the seat section, means supporting the back section comprising a downwardly extending rib and a link connected at one end to the lower end of the rib and connected at the other end to the upper end of the lever to which the rear of the seat section is connected, a spring tending to pull the seat section rearwardly and to swing the back section forwardly into alignment with the intermediate section, the back and intermediate sections moving relatively upward as the seat moves forwardly in the frame.

12. In a reclining chair, a chair frame, pivotally interconnected seat, intermediate and back sections, means mounting the seat section for forward and rearward swinging movement in the chair frame, and comprising an upwardly extending lever pivotally secured to the chair frame and pivotally connected at its lower end to the rear end of the seat section, means mounting the intermediate section on the chair frame in an inclined position extending upwardly from the rear of the seat section the intermediate section being adapted to be inclined to a lesser degree by the forward movement of the seat section, means supporting the back section comprising a downwardly extending rib and a link connected at one end to the lower end of the rib and connected at the other end to the upper end of the lever to which the rear of the seat section is connected, a perforated bar secured to the chair frame and projecting parallel with and below the seat section, and a pin slidably supported at the edge of the seat section and engageable with any one of the perforations of the bar.
